UNITED STATES PATENT OFFICE.

EDWARD DANNER, OF TOLEDO, OHIO, ASSIGNOR TO THE LIBBEY GLASS COMPANY, OF TOLEDO, OHIO, A CORPORATION OF OHIO.

BAR AND TUBING FEEDING AND SEVERING MEANS.

1,220,201.

Specification of Letters Patent. Patented Mar. 27, 1917.

Application filed May 3, 1916. Serial No. 95,069.

To all whom it may concern:

Be it known that I, EDWARD DANNER, a citizen of the United States, and a resident of Toledo, in the county of Lucas and State 5 of Ohio, have invented a certain new and useful Bar and Tubing Feeding and Severing Means; and I do hereby declare the following to be a full, clear, and exact description of the invention, such as will enable 10 others skilled in the art to which it appertains to make and use the same, reference being had to the accompanying drawings, and to the characters of reference marked thereon, which form a part of this specification. 15

This invention relates to use more particularly in connection with apparatus for continuously forming molten material, such for instance as glass, into cane or tubing, 20 and has for its object the provision of mechanism for continuously drawing cane or tubing from a forming apparatus and successively severing it into sections of predetermined length in a simple and efficient 25 manner.

The invention is fully described in the following specification, and while, in its broader aspect, it is capable of embodiment in numerous forms, a preferred embodiment 30 thereof is illustrated in the accompanying drawings, in which—

Figure 1 is a top plan view of an apparatus embodying the invention, with a part of the work breaking-off and delivering 35 mechanism removed. Fig. 2 is a side elevation of the mechanism shown in Fig. 1. Fig. 3 is an enlarged side elevation of the work breaking-off and delivering means. Fig. 4 is a section on the line 4, 4 in Fig. 3. 40 Fig. 5 is an enlarged end elevation of the apparatus, with a part in section on the line 5, 5 in Fig. 1. Fig. 6 is an enlarged section on the line 6, 6 in Fig. 1, with a part broken away. Fig. 7 is a fragmentary section on 45 the line 7, 7 in Fig. 6. Fig. 8 is an enlarged section on the line 8, 8 in Fig. 1, with parts removed. Fig. 9 is a section on the line 9, 9 in Fig. 8. Fig. 10 is a section on the line 10, 10 in Fig. 9. Fig. 11 is a detail of 50 the work guiding means at the entrance end of the apparatus. Fig. 12 is an enlarged detail of a portion of one of the work feeding chains. Fig. 13 is a section on the line 13, 13 in Fig. 12. Fig. 14 is an unfolded plan 55 view of the work coacting pad portion of

one of the work feeding chains. Fig. 15 is an enlarged plan view of the slide-head and parts carried thereby, with portions broken away and in section. Fig. 16 is a section on the line 16, 16 in Fig. 15. Fig. 17 is a section on the line 17, 17 in Fig. 16. Fig. 18 is an enlarged section on the line 18, 18 in Fig. 16. Fig. 19 is a plan of one of the gasket members employed in connection with the parts shown in Fig. 18. Fig. 20 is an enlarged section on the line 20, 20 in Fig. 15, with parts in full. Fig. 21 is a left end view of the mechanism shown in Fig. 20, with the work cutting wheel and the guard therefor removed and with parts in 70 section. Fig. 22 is an enlarged view of a portion of the slide-head driving means. Fig. 23 is an enlarged section taken approximately on the line 23, 23 in Fig. 1; and Fig. 24 is a side elevation of a portion 75 of the mechanism illustrating the course of movement of the work cutting wheel.

Referring to the drawings, 1 designates the frame of the apparatus, which frame is preferably in the form of a platform and mounted on a set of wheels 2 to facilitate a moving of the frame from one position to another. The work A, which may be of continuous tubular or bar form, first passes between a pair of guide rolls 3, which are 80 mounted on vertical spindles at one end of the frame 1, and then enters between the co-operating portions of a pair of upper and lower work feeding chains 4, 4. These feed chains are mounted in vertically spaced relation on respective sets of sprocket wheels 5, 5, the front and rear sprocket wheels of the lower set being keyed respectively to shafts 6 and 7, and the front and rear 85 sprocket wheels of the upper set being keyed 90 respectively to shafts 8 and 9. The lower set of shafts 6, 7 are mounted in the lower portions of respective bearing standards 10, 11, (shown in detail in Figs. 8, 9 and 10,) which standards are fixedly mounted on and rise from the frame 1 at one side portion thereof and in longitudinally spaced relation with respect thereto. The upper set of shafts 8, 9 are mounted in respective bearing blocks 12, 13, which are mounted for vertical adjustment on the adjacent sides of the upper end portions of the respective bearing standards 10 and 11 to permit a vertical adjustment of the upper set of shafts with 100 respect to the lower set. 105

The bearing blocks 12 and 13 are threaded, in the present instance, to respective adjusting screws 14, 15, which are journaled in vertically disposed position in the respective bearing standards 10 and 11, whereby a turning of the screw shafts will effect a vertical adjustment of the respective bearing blocks 12 and 13. The upper ends of the screw shafts 14 and 15 are connected by respective sets of miter gears 16 to a shaft 17 which connects the upper ends of the bearing standards 10 and 11, being suitably journaled therein, and has a crank 18 at its rear end to facilitate a hand turning thereof in one direction or the other as it may be desired to effect a raising or lowering of the bearing blocks 12, 13.

The working portions of the chains 4, 4 are held in yielding contact with the work 20 A, as it is fed forward thereby, by the co-operative action of a stationary platform 19, over which the working portion of the lower chain travels in contact therewith, and a plurality of pressure plates 20, which are 25 mounted above the working portion of the upper chain in a manner to cause said chain to have a yielding downward pressure on the work. The platform 19 is mounted on brackets 21, 21, which are mounted on and 30 rise from the frame 1. Each pressure plate 20, in the present instance, has a stem 22 projecting upward therefrom into a registering socketed part 23 of an overhead frame part 24, which frame part is carried at the 35 upper ends of a pair of upright posts 25, 25. Each post 25 projects downward into a registering opening 26 in the frame 1 (see Fig. 6) for free vertical movements therein and has a sprocket-wheel 27 threaded thereon 40 and resting at the lower end of its hub on the frame 1, whereby a turning of the sprocket wheel 27 will effect a vertical adjustment of the post. A set screw 28 removably secures the frame part 24 to each post 45 25. A pair of plates 29 are bolted to the frame 1 at opposite sides of the lower end portion of the hub of each sprocket wheel 27 and engage over an annular flange on said hub portion, as shown in Figs. 6 and 7, to 50 rotatably hold the sprocket wheel to the frame 1. The sprocket wheels 27, 27 are connected by a chain 30 to cause a turning of the sprocket wheels in unison.

A coiled compression spring 31 (Fig. 6) 55 is mounted in each socketed part 23 and acts against the respective stem 22 to cause its pressure plate 20 to have a yielding downward pressure on the working portion of the upper feed chain 4. It is evident that the 60 pressure of the plates 20 on the chain and the consequent force of gripping of the work A by the working portions of the two chains 4, 4 can be adjusted to suit the requirements of the particular case by a raising or lowering 65 of the posts 25. This adjustment is also

effected upon a changing of the size of the work operated on.

The links of each chain 4 are connected by shafts 32 (see Figs. 12 and 13), and alternate shafts carry rollers 33 at their ends 70 which coact with the respective platform 19 and pressure plates 20 when traveling therebetween. Each chain 4 is also provided in equidistantly spaced relation with chairs 34, which carry work engaging pads 35 at their 75 outer sides. The chairs 34 are substantially U-shape in cross-section and have their leg portions mounted on and connecting spaced shafts 32 of the chain, such connection being sufficiently free to permit a flexing of the 80 chain as it passes around the sprocket wheels. The pad 35 comprises a holder member 35^a and a work engaging part 35^b, which is held in position on the shaft by the holder 35^a. The body portions of each pad part 35^a and 85 35^b are of rectangular form and substantially of the same length, with the side edges of the holder part 35^a projecting beyond the side edges of the pad part 35^b to form extensions 35^a for folding over the side edges of 90 the part 35^b, as shown in Fig. 13. The ends of each of the pad parts are also provided with tongue extensions 35^c, with the extension 35^c of the holder part of greater length than the extensions 35^c of the pad part to 95 permit an endwise doubling of the holder extension 35^c over the pad part extension 35^c. The pads 35 are secured to the chairs 34 by a doubling of the end extensions 35^c, 35^c under the respective end portions of the 100 chair 34, as shown in Fig. 12. The pads on the separate chains 4, 4 are arranged to have opposed engagement with a work piece A passing therebetween.

The guide rolls 3, 3, which are disposed at 105 the rear of the feed chains 4, 4 are carried by respective vertically disposed spindles 36, 36 (see Fig. 11), which spindles are pivoted intermediate their ends, as at 37, to respective vertically projecting carrying arms 38, 110 which arms are enlarged at their lower ends and mounted on a horizontally disposed shaft 39 in respective right and left threaded connection therewith, whereby a turning of the shaft with respect to the bearing arms 115 38 will cause said arms to have like inward and outward adjusting movements. The shaft 39 is rotatably mounted in the inner forked end of a bracket 40, by which it is held against endwise movement, said bracket 120 being fixed to and rising from the rear end of the frame 1. The lower ends of the spindles 36 are disposed at the inner sides of the carrying arms 38 and each is yieldingly connected at its lower end to its carrying arm 125 by a bolt 41, which projects outward through the spindle end and through a registering opening in the carrying arm, and has a coiled compression spring 42 mounted on its outer end portion without the carrying arm 130

and in thrust engagement at its inner end with said arm. It is evident that this yielding connection between the spindles 36 and their carrying arms causes the rolls 3, 3 to 5 exert an opposed yielding pressure against the work A passing therebetween.

Power for driving the work feeding chains 4, 4 is derived, in the present instance, from a motor 43 mounted on the platform 1 (see Fig. 1), the shaft of said motor carrying a pinion 44 in driving connection with a gear 45. The gear 45 is mounted on a shaft 46 that is journaled transversely of the frame 1 in a suitable bearing 47 provided thereon and carries a pinion 48 in mesh with one of a pair of meshing gears 49 disposed one above the other and carried one by the chain driving shaft 6 and the other by the chain driving shaft 8, which shafts for such 20 purpose are projected from the bearing standard 10 across the frame 1 and are journaled in a bearing standard 50. The upper shaft 8 is provided intermediate the bearings 12 and 50 with a flexibly connected section 25 8^a, which permits a vertical adjustment of the sprocket wheel carrying end of the shaft with respect to the gear carrying end thereof. It will be understood that the gears 44, 45, 48 and 49 are interposed between the motor and chain shafts for the purpose of reducing the speed of driving of the chains the desired extent with respect to the speed of the motor shaft, and that such connection may be changed to suit the exigencies of the 30 particular case.

The work A, after passing between the feed chains 4, 4, enters between a pair of horizontally spaced guide rolls 51, thence passes over a vertically yielding pressure 40 table 52, and next enters a registering portion of the work breaking-off and delivery-wheel 53, by which the work A is intermittently broken into sections of predetermined length and then delivered from the machine. 45 It is preferable to provide rearwardly flaring stationary guides 54 and 55 in position to respectively guide the work between the rolls 51 and into the registering receiving portion of the wheel 53, should the work bar 50 or tubing break off at the rear of either of said members, as frequently occurs when the work is of a brittle nature, like glass. The guide 54 is carried by an arm 56, which fixedly rises from an adjacent portion of the 55 frame 1, and the guide member 55 is carried by a bearing standard 57 rising from the forward end portion of said frame. The guide rolls 51 are mounted in a similar manner to the guide rolls 3, 3 and the specific 60 mounting of the same need not therefore be described.

The pressure table 52 is elongated lengthwise of the work and is pivoted adjacent to its rear end, as at 58, to a supporting stand- 65 ard 59, which rises from the frame 1. The

forward end of the table 52 is caused to have yielding upward pressure exerted thereon against the under side of the work A (for the purpose hereinafter described) by a coiled compression spring 60, which is 70 mounted between portions of the table and its standard forward of the pivot 58. The standard 59 is preferably mounted for adjustment lengthwise of the frame 1 to vary the point of upward pressure of the table 75 52 on the work as occasion may require.

A shaft 61 is mounted at its ends in bearing standards 62 and 63 rising from the frame 1 and is disposed at one side of the pressure table 52, the right hand side thereof, in the present instance, with respect to the direction of feed of the work, and in parallel relation to such direction of feed. This shaft is driven at a high rate of speed by a motor 64, which motor is mounted on 85 the frame 1 and has belt and pulley connection 65 with the forward end of said shaft.

A pulley 66 is splined on the shaft 61 for longitudinal movements thereon between its bearings, and the hub ends of the pulley are 90 preferably extended therefrom in sleeve form, as shown at 67 (see Fig. 15). Bearing sleeves 68 and 69 are respectively mounted for free rotation on the front and rear hub ends 67, and these sleeves form bearings 95 for the respective arms of a forked slide-head 70, which straddles the pulley 66, thus adapting said slide-head to have horizontal reciprocatory movements with the pulley 100 axially of the shaft 61, and vertical rocking movements with respect to said pulley and shaft transversely thereof. The outer end of the head 70 carries a bearing fork 71, the arms of which are horizontally spaced and form bearings for a horizontally disposed 105 shaft 72 and carry ball bearings 73 therefor (see Figs. 15 and 20). The shaft 72 has a pulley 74 keyed thereto intermediate the bearing arms of the fork 71, and this pulley is connected by a belt 75 to the pulley 66. 110 The fork 71 is shown, in the present instance, as having a stem 71^a projecting from the inner end thereof and into a registering socket 70^a in the outer end of the slide-head 70, for reciprocatory movements therein, it being prevented from turning therein, however, by a key 70^b (Fig. 16). A nut 71^b is threaded on the inner end portion of the stem 71^a and is held in thrust contact with the outer end of the slide-head 70 by the belt 115 75, which connects the pulleys 66 and 74. A tightening or loosening of the belt may be effected by turning the nut 71^b on the stem, and the nut is locked in adjusted position by a pin 71^c, as shown in Fig. 16. 120

A work cutting wheel 76 is fixedly mounted on one end of the shaft 72, the forward end thereof, in the present instance, without the bearing fork 71 and is disposed over the work A in position to be lowered into 130

contact with the top of the work by a downward rocking of the slide-head 70, the forward and backward strokes of said wheel with respect to the table 52, upon a forward and backward reciprocation of the slide-head 70, being indicated by the dotted lines *a*, *b* in Fig. 24, the lower line designating the forward stroke and the upper line the rearward stroke of the wheel. It will be noted from the lower line *a* that the lower edge of the cutter wheel 76 moves downward into contact with the work A during the initial portion of its stroke, then remains for a short period in contact with the work and then rises from engagement with the work during the final portion of the forward stroke, the point of contact of the wheel with the work being in opposition to the forward yieldingly supported end portion of the pressure table 52. The means for effecting such vertical movements of the cutter wheel will be hereinafter described.

The wheel 76 is intended to cut a surface groove in the work each time it is moved into contact therewith, such groove not being of sufficient depth, however, to cause a severing of the work at such point at this period in a cycle of operations of the machine, the final severing action being caused by the action of the wheel 53 on the work, which wheel is intended to intermittently revolve and exert a transverse strain on the work in advance of the cut to effect a breaking off of the work at such weakened point. The frictional coaction of the wheel 76 with the work also causes a localized heating of the work at the point of contact so that a strain is set up within the heated part thereby facilitating a breaking off of the work at the grooved point.

A lubricant is retained within one bearing arm of the fork 71 by plates 77 secured to opposite sides thereof while plates 78 are secured to opposite sides of the other arm of said fork to retain a lubricant in contact with its bearing.

A guard or housing 79 for the cutter wheel 76 is secured to the outer plate 78 by screws 80 or in any other suitable manner.

A hand adjusting screw 81 is vertically threaded into the top of the forward fork arm 71 and carries a block 82 for vertical adjustment therewith, said block projecting transversely from the screw through a registering slot or notch 83 in the outer plate 78 and carrying a pair of work guiding fingers 84 at its outer end. The fingers 84 are carried at their upper ends by a common pivot screw 85, projecting from the forward end of the block 82, and project outward, downward and then inward between the outer plate 78 and the wheel inclosing portion of the guard 79, and have their lower ends disposed in spaced relation below the lower horizontal edge of the cutter wheel 76

and in position to permit the passage of the work A therebetween. These guide fingers follow the course of movements of the cutter wheel and are intended to hold the work against transverse movements during the cutting action of the wheel thereon.

The lower end portions of the guide fingers 84, 84 are connected by and yieldingly drawn toward each other by a coiled contractile spring 86, and the inward relative movements of said fingers are limited by stop-nuts 87, 87, which have right and left threaded connection with an adjusting screw 88. The screw 88 is journaled for free rotary movements in a pair of spaced bearing bosses 89, projecting from the outer plate 78, and carries a collar 90 between said bosses to prevent endwise movements of the adjusting screw therein. The nuts 87 are positioned to coact with the inner edges of the respective guide fingers 84 to limit the inward movements thereof, and a turning of the screw 88 in one direction or the other causes the nuts to move inward or outward in unison thereon, as is apparent. It is evident that a raising or lowering of the adjusting screw 81 with respect to the fork 71 will effect a corresponding raising or lowering of the guide fingers 84 as it may be desired to vertically adjust them with respect to the work.

A guide plate 91 is disposed in rearwardly inclined position below the fork 71, having its rear end attached to the rear arm of the fork 71, as at 92, and its forward end adjustably connected to the forward fork arm by a U-shaped yoke 93, the legs of which project upward from the plate 91 and are provided with vertical slots 94 for receiving a bolt 95, projected through the lower portion of the fork arm. The plate 91 terminates at its forward end adjacent to the rear side of the fingers 84 in position to guide an end of the work A with respect to said guide fingers should the work become broken off at a point at the rear of the guide fingers.

The means employed for reciprocating the slide-head 70 on the shaft 61 will now be described. Mounted in bearing blocks 96, which rise from the frame 1 at the right hand side of the shaft 61, are a pair of shafts 97, which are transversely spaced lengthwise of said frame and each carries a sprocket wheel 98. These sprocket wheels are connected by a sprocket chain 99, and such chain is provided at a point thereon with a transversely disposed shaft 100 carrying a roller 101 at each end thereof. A yoke or slide-frame 102 is mounted for sliding movements lengthwise of the shaft 61 on a slide-base 103 and has arms 102^a projecting therefrom and carrying the respective sleeves 68 and 69, which in turn carry the slide-head 70 (see Figs. 6, 15 and 22). 130

The outer side of the yoke or slide-block 102 is provided with a boss 104, which coacts with a pair of plates 105 secured to its outer end to form an opening 106, which takes 5 over the chain 99 and sprocket wheels carrying the same, and is permitted to have backward and forward movements over said chain and sprocket wheels. The side walls of the opening 106 are provided with vertically disposed guide grooves 107 in which the rolls 101 on the respective ends of the shaft 100 travel. It is evident that the yoke 102 will have backward and forward movements communicated thereto by the 10 rolls 101 as said rolls follow the successive backward and forward movements of the portion of the chain 99 to which attached when said chain is driven, and that said rolls will move vertically in the grooves 107 15 as they pass around the respective sprocket wheels with the chain. The plates 105, which are secured to the outer side of the boss 104, are spaced at their inner ends to permit the passage of the shafts 97 therebetween as the yoke is reciprocated. This 20 form of driving means for the cutter wheel carrying parts causes said parts to have rapid uniform forward and backward strokes which are slowed up adjacent the 25 limits thereof and enable the major portions of each stroke to be maintained at a uniform speed which is the same as the speed of forward feeding movement of the work, thereby causing the cutter wheel when acting on 30 the work to move therewith without any relative variation in speed.

108, 108 (Fig. 15) designate lubricant retaining collars, which are secured to the outer sides of the yoke-arms 102^a in encircling relation to the shaft 61 and retain a lubricant in contact with the ball bearings 109 for the respective sleeves 68 and 69. The shaft 97, which serves as the drive shaft 40 for the chain 99 has a sprocket wheel 110 thereon, which is connected by a chain 111 to a sprocket wheel 112 on the feed chain driving shaft 8 (see Figs. 1 and 6), said sprocket wheels 110 and 112, the sprocket wheels 98 and the sprocket wheels 5 being 45 of like size so that the chain 99 is driven at the same speed as the feed chains 4.

The lower inner edge portion of the yoke or slide-block 102 has a boss 113 projecting therefrom and loosely receiving a shaft 114 55 (see Fig. 23), which is mounted below the shaft 61 in parallel relation thereto and has one end journaled in the bearing bracket 63 and provided without said bracket with a hand-wheel 115 to facilitate a hand turning 60 of the shaft. The shaft 114 has nuts 116 mounted on opposite end portions thereof in respective right and left threaded connection therewith, said nuts having coaction with registering portions of the slide-base 65 103, whereby they are held against turning

and permitted to move lengthwise of the shaft 114. A coiled compression spring 117 is mounted on the shaft 114 at each side of the yoke boss 113, and this spring is intended to coact with the respective nuts 116 70 to serve as a bumper for the slide frame or yoke 102 and to facilitate a reversal of the movement thereof. It is evident that a relative inward or outward adjustment of the nuts 116 can be effected by a turning of the 75 shaft 114 in one or the other direction and a consequent inward or outward adjustment of the springs 117 accomplished.

The means employed for vertically rocking the slide-head 70 to raise and lower the 80 cutter wheel 76 with respect to the work at predetermined points in a forward stroke of said slide-head will now be described. A shaft 118 is mounted below the slide-head 70 before the vertical plane of the shaft 61, being journaled at one end in the bearing standard 57 and at its other end in a bearing bracket 119 secured to the adjacent end portion of the slide-base 103 (see Fig. 1). This shaft has connection through a pair of gears 90 120 (Figs. 1 and 6) with a short shaft 121 which is mounted in the bracket 119 and has bevel gear connection 122 with the drive shaft 6 for the feed chains. The speed of driving of the shaft 118 is so timed with 95 respect to the speed of driving of the feed chains 4 and the reciprocatory movements of the slide-head 70 that the shaft 118 makes one complete revolution for each complete cycle of operations of the machine, or a 100 single complete forward and backward movement of said slide-head. A cam-wheel 123 is splined on the shaft 118 for axial reciprocatory movements thereon and turning movements therewith, said wheel having a 105 peripheral groove 124 and a cam working surface 125 provided circumferentially around different portions thereof (see Fig. 18). An arm 126 is carried at one end by the sleeve 68 on the shaft 61 and has its other 110 end projecting transversely from said shaft under the slide-head 70 and terminating over the cam-wheel 123 with a part 126^a thereof forked to straddle the grooved portion 124 of the cam-wheel. The arm 126 carries a roll 115 127 at one side of said forked portion in position to ride on the cam surface 125 of the wheel, whereby a rotation of the cam-wheel causes vertical rocking movements to be imparted to the arm 126 in accordance with 120 the formation of said cam surface. A stud 128 projects upward from the free end portion of the arm 126, in the present instance, into a registering socket in the under side of the slide-head 70 and receives the downward 125 end thrust of the lower end of a set screw 129, which is threaded down through a portion of the slide-head 70 (see Figs. 15, 16 and 17). It is evident that a vertical adjustment of the cutter wheel 76 with respect to 130

the work can be effected by an adjusting of the screw 129 in the slide-head, the slide-head being thereby raised or lowered with respect to the arm 126. The screw 129 is secured in adjusted position by a set screw 130.

It is found in practice quite important to prevent the accumulation of dirt and particles of the work within the spline grooves 118^a of the shaft 118, especially when operating on glass, as it is found that small particles of glass fall in said grooves and not only prevent a free movement of the slide parts but sometimes cause a locking of said parts against movement. For this reason I have provided a cleaning gasket 131 at each end of the cam-wheel 123, each of said gaskets being set in a recess in the end of the cam-wheel and secured therein by a collar 132, which is secured to the end of the wheel by screws or in any other suitable manner (see Figs. 17, 18 and 19). Both the gasket and collar have spurs 133 projecting inward therefrom and fitting into the respective groove of the shaft 118. The splines 134 are held centered within the cam-wheels and prevented from pounding against and damaging the spurs 133 of the gasket by set screws 135, which are threaded through the respective collars 132 and project through the gaskets in position to engage the respective ends of the splines 134.

The work breaking-off and delivery wheel 53 is journaled at its rear end in a part 57^a of the bearing standard 57 and is disposed with its axis parallel to but slightly offset from the line of travel of the work A, said wheel being disposed forward of the bearing standard by which its shaft is carried. The wheel is composed of a plurality of plates 138, which project tangentially from a circle concentric to its axis of rotation and are successively positioned therearound, six being employed in the present instance, and secured at their inner ends to respective sides of the shaft 137, which is made of hexagonal form in cross-section for such purpose, as shown in Fig. 4. The plates 138 coöperate to form a plurality of pockets around the periphery of the wheel, which pockets are of a length corresponding substantially to the maximum length of the work piece sections to be cut or broken from the work bar or tube. The inner or rear end of each pocket is provided with an end plate 139 having an opening 140 therein flush at one side with one of the bars 138 and through which the work enters a registering pocket of the wheel. Upon a turning of the wheel 53 in the direction indicated by the arrow in Fig. 4, after a predetermined length of the work bar or tube has been projected into a registering pocket thereof, the plate 139 strikes the work bar or tube slightly in advance

of the point thereof which was cut by the cutter wheel 76 and effects a breaking in two of the bar or tube at its weakened point. The turning of the wheel in addition to causing a breaking-off of work sections also moves the pocket containing the broken-off section either to or toward the section delivery position thereof and moves the next pocket in order in position for the advancing work to enter the same.

The intermittent turning of the wheel 53 is controlled by a set of gears 141 (Fig. 5) of the Geneva type, the pin carrying member of which is mounted on a shaft 142 intermediate the shafts 137 and 118 and is in geared connection with the shaft 118 through the medium of the gears 143. The gears 143 are of like size so that a pocket advancing movement is communicated to the wheel 53 at each complete rotation of the shaft 118.

The operation of my machine is as follows: It will be understood that the work bar or tube A advances from the furnace or other source of supply between the guide rolls 3, 3 and thence between the set of feed chains 4, 4, by which it is drawn forward at a uniform predetermined speed from the furnace or forming means, the gripping pressure of the working portions of the feed chains 4 on the work being regulated by a turning of the sprocket wheels 27 on the posts 25, which imparts vertical movement to the frame part 24 and varies the tension of the spring 31 on the stem 22 of the pressure plate 20. The feed chains 4, 4 and the sprocket wheels carrying the same are also adapted to have relative vertical adjustment by a turning of the crank 18 and shaft 17 to which it is attached, which turning communicates rotary movements to the adjusting screws 14, 15 for the respective bearing blocks 12 and 13, which carry the shafts for the upper set of sprocket wheels 5. The work, after passing between the feed chains 4, 4, passes through the guide 54, then between the guide rolls 51, then under the cutter wheel 76 and over the pressure table 52, in contact with the latter, and thence through the guide member 55 and into a registering pocket of the work breaking-off and delivery wheel 53. As the work advances the slide-head 70 and other parts which carry the cutter wheel 76, and which connect said slide-head with the drive chain 99, are caused to be reciprocally moved on the shaft 61 lengthwise of the direction of feed of the work and with the speed of movement of each forward stroke, at least, thereof the same as the speed of advancing movement of the work A. It will be understood that the shaft 118, which carries the cam-wheel 123, has a single complete rotation at each cycle of movements of the cutter wheel carrying parts, or a complete for-

ward and backward movement thereof, and that the cam surface 125 of the cam-wheel is so formed with respect to its turning that the course of movement of the lower edge 5 of the cutter wheel during the forward or working stroke thereof is as indicated by the dotted line *a* in Fig. 24, which movement lowers the cutter wheel into engagement with the upper surface of the work and 10 causes it to maintain such engagement for a predetermined portion of its movement, after which the wheel is raised to its elevated position and maintains such elevated position during its rearward stroke, as shown 15 by the dotted line *b* in Fig. 24. The action of the cutter wheel 76 on the work causes a shallow notch to be cut in the surface of the work at the point where it is desired to have the work subsequently severed or 20 broken and the frictional coaction of the cutter wheel with the work in addition to cutting or notching the same also effects a localized heating thereof at the point of contact so that an abnormal strain is set up 25 in the glass and renders it more brittle at such point to facilitate breaking off. The point of contact of the cutter wheel with the work is opposed to the end portion of the table 52, which bears upward against the 30 work, thereby retaining the work in yielding contact with the cutter wheel during the cutting operation. The cutter wheel is driven at a high rate of speed from the motor 64, which has belted connection with 35 the shaft 61, and said shaft in turn has belted connection with the cutter wheel shaft. The drive chain 99 is connected to one of the drive shafts for the feed chains 4, 4 and is driven at the same speed as said 40 feed chains. When a predetermined length of work has moved into a registering pocket of the breaking-off and delivery wheel 53 the wheel is given, in the present instance, 45 a one-sixth turning movement, which causes the plate 139 at the rear end of the pocket in which the work is feeding to strike the work slightly forward of the notched or weakened point thereof, which effects a 50 breaking in two of the work at such point. Such movement of the wheel also moves the next pocket in order in position for the advancing work to enter the same preparatory to the next breaking-off movement thereof. It is thus evident that the work is cut and 55 later broken off in sections of equal length during a continuous forward feeding thereof and that the cut-off sections are delivered from the pockets of the wheel 53 by gravity as the wheel is successively turned.

60 In the present use of the machine embodying my invention it is driven at a speed to cause an advancing or forward drawing of the work bar or tube at approximately 140 to 150 feet a minute. This, however, may be increased or diminished, as desired.

While I have herein shown and described one specific embodiment of my invention for illustrative purposes and have disclosed and discussed in detail the construction and arrangement incident to one specific application thereof, it is to be understood that the invention is not limited to the detail or relative arrangement of the parts, but that it is capable of numerous modifications either in entirety or in the different sub-combinations 70 thereof without departing from the spirit of the claims.

Having thus described my invention, what I claim as new, and desire to secure by Letters Patent, is—

1. In a machine of the class described, means for imparting continuous lengthwise feeding movements to the work bar or tube, a pressure member having a yielding transverse pressure against a part of the work, 80 and a cutter member periodically operable to have forward movements with the work at a uniform speed therewith and to move into and out of engagement with the work in opposition to said pressure member at 85 predetermined points in a forward feeding movement of said cutter member.

2. In a machine of the class described, means for imparting continuous lengthwise feeding movements to a work bar or tube, 90 slide means reciprocally movable lengthwise of the work feed and also movable transversely thereof, a cutter part carried by said means, an endless chain connected to said means and operable by a continuous movement thereof in one direction to impart both forward and backward reciprocatory movements to said slide means, said movement being uniform in speed to the feeding movements of the work, and means for periodically moving said slide means transversely of the work to periodically place the cutter part in engagement with the work.

3. In a machine of the class described, work cutter carrying means mounted for reciprocatory movements and having a guide part, an endless chain continuously movable in one direction and having movable engagement with the guide part of said means whereby said means is caused to move backward and forward with said chain part as the chain is moved.

4. In a machine of the class described, means mounted for reciprocatory movements and having a guide part extending 120 transversely of its direction of movement, and an endless chain having a part projecting transversely therefrom into engagement with the guide part of said means and operable to impart reciprocatory movement to 125 said means when the chain is continuously moved in one direction.

5. In a machine of the class described, a reciprocally movable means having a cutter part, rotatable cam means mounted for re- 130

ciprocatory movements with said first means and operable to periodically impart movements to said means transverse to its reciprocatory movements to move the cutter part 5 into and out of work coacting position.

6. In a machine of the class described, a slide frame mounted for reciprocatory movement, a chain drive having connection with and operable to impart reciprocatory movements to said frame, a head having rocking connection with said slide frame and movable therewith, a cutter member carried by said head, means for driving said cutter member, and means for imparting rocking 10 movements to said head at predetermined points in a reciprocatory movement thereof.

7. In a machine of the class described, a driven shaft, means mounted for sliding movements on said shaft and having a head 20 movable in a plane transverse to the shaft, a fork removably carried by said head, a shaft mounted in said fork, means connecting said driven and fork shafts for communicating rotation from one to the other 25 and operable to maintain the fork in connection with said head, a cutter wheel carried by said fork shaft, and rotary cam means periodically operable to impart transverse movements to said head with respect to 30 said driven shaft.

8. In a machine of the class described, a driven shaft, a slide head mounted for reciprocatory movements lengthwise of said shaft, said head having a socket in its outer 35 end, a fork having a stem loosely projected into said head socket, a stop-nut threaded on said fork stem and coacting with the head to limit the extent of insertion of the stem into the head, a cutter wheel shaft carried 40 by said fork, and means for communicating rotation from one to the other of said shafts and serving to maintain the fork stem at the limit of its movement on said head.

9. In a machine of the class described, 45 slide means having a part mounted for rocking movements, a cutter wheel carried by said rocker part, means for imparting reciprocatory sliding movements to said slide means, means for imparting rocking movements to said rocker part at predetermined 50 points in the sliding movement thereof, said rocking means comprising a shaft parallel to the rocking axis of said part, and a cam 55 slidably mounted on said shaft and rotated at a predetermined speed, and means for adjusting said rocker part with respect to the means for rocking the same.

10. In a machine of the class described, a shaft, means mounted for axial reciprocatory movements on said shaft, and having a part mounted for rocking movements transverse to said shaft, means for imparting reciprocatory movements to said first means, a cutter member carried by said rocker part, 65 a second shaft, a cam wheel splined to said

shaft for rotation therewith and axial movements thereon, an arm projecting from said first means for movements therewith and having a part coacting with said cam wheel whereby rocking movements are imparted to 70 said arm from said wheel when rotated, and adjustable connection between said arm and rocker part for communicating rocking movements from one to the other thereof, and means for driving said second shaft at 75 a predetermined speed.

11. In a machine of the class described, a shaft, means mounted for reciprocatory movements lengthwise of said shaft and having a part movable transversely of said 80 shaft, means for imparting reciprocatory movements to said first means, a cutter wheel carried by said rocker part, means for driving said cutter wheel, a cam wheel splined to said shaft, connection between said cam 85 wheel and rocker part for communicating predetermined rocking movements to said part from a rotation of said cam wheel, means for driving said shaft, and gasket means carried by said cam wheel and engaging 90 within the splined groove of the shaft for cleaning the same as the wheel reciprocates theron.

12. In a machine of the class described, a reciprocally movable slide frame, work coacting means carried by said frame for movements therewith, means for imparting reciprocatory movements to said slide frame, adjustable bumper means for engagement with said slide frame adjacent the ends of 100 its movements, and means for periodically moving said work coacting part into and out of engagement with the work as the slide frame is reciprocated.

13. In a machine of the class described, 105 means for imparting continuous lengthwise feeding movements to a work bar or tube, means for successively acting on the work to weaken the same at spaced points lengthwise thereof, and a rotating member for subsequently 110 acting on the work to successively break sections from the work at the weakened points thereof and to deliver such sections from the machine, said member having its axis of rotation lengthwise of the 115 work feed.

14. In a machine of the class described, means operable to impart continuous lengthwise feeding movements to a work bar or tube, means operable to successively act on 120 the work to weaken the same at longitudinally spaced points therein and to move with the work at uniform speed therewith during each weakening operation, a rotating wheel-like member operable to successively break sections from the work at the weakened points and to deliver the broken-off sections to a predetermined position, and means for intermittently rotating said member in one direction only. 130

15. In a machine of the class described through which a work bar or tube is continuously fed, means operable to successively partially sever the work at longitudinally spaced points therein, and rotary means continuously operable to receive and complete the breaking of the work in two at the partially severed points and having its axis longitudinal to the direction of movement of the work. 5
16. In a machine of the class described through which a work bar or tube is continuously fed, reciprocatory means periodically movable with the work and operable to partially sever the work during such movement, and a rotary wheel-like member having work receiving pockets and subsequently operable to successively break the work in two at the partially severed points. 15
17. In a machine of the class described through which a work bar or tube is continuously fed, means for successively acting on the work at longitudinally spaced points to weaken the same, and means having an intermittently rotating member provided with peripheral pockets for subsequently acting on the work to successively break the same in two at the weakened points. 20
18. In a machine of the class described through which a work bar or tube is continuously fed, means reciprocally movable lengthwise of the work and having its forward speed of movement the same as that of the work, said means having a part movable to coact with the work during a predetermined portion of each forward movement of the means to partially sever the work, and a single rotary member for subsequently receiving and acting on the work to break the same in two at the partially severed points thereof, said member having work breaking parts at an end thereof. 30
19. In a machine of the class described through which a work bar or tube is continuously fed, means reciprocally movable lengthwise of the work and having its forward speed of movement the same as that of the work, said means having a part movable to coact with the work during a predetermined portion of each forward movement of the means to partially sever the work, and rotary means for subsequently acting on the work to receive and break the same in two at the partially severed point thereof and to deliver the broken-off sections of the work from the machine, the axis of said rotary means being longitudinal to the work feed. 45
20. In a machine of the class described, means for imparting lengthwise feeding movements to a work bar or tube, means reciprocally movable lengthwise of the feed of the work and having a cutter part movable transversely to the work, means oper- 50
- able to periodically move said cutter part transversely to the work into and out of cutting engagement therewith, and means for receiving and subsequently breaking off the work at the partially severed points thereof, said last means having step-by-step rotary movements in one direction only. 70
21. In a machine of the class described, means for successively acting on a forwardly feeding bar or tube to weaken the same at longitudinally spaced points, a wheel disposed with its axis lengthwise of the feeding movement of the work and at one side thereof to permit the work to enter the wheel, said wheel when rotated being operable to impart a transverse strain on the work to successively break it in two at the weakened points therein, and means for imparting predetermined rotary movements to said wheel. 75
22. In a machine of the class described, a wheel having peripherally opening pockets extending lengthwise thereof and open at one end to permit a work bar or tube to feed lengthwise into a registering pocket, said wheel having end parts which, when the wheel is rotated, strike against and break the work in two, means for imparting intermittent rotary movements to said wheel to place successive pockets in register with the work, and means operable to weaken the work at successive points before being acted on by said wheel. 80
23. In a machine of the class described, an endless flexible member, means guiding the course of movement of said member, means for driving said member, work cutter carrying means mounted for reciprocatory movements, and means connecting said cutter carrying means and member for imparting both backward and forward reciprocatory movements to the former when the latter is continuously moved in one direction. 95
24. In a machine of the class described, a pair of guide wheels one acting as a driving means, an endless flexible member connecting and extending around said wheels, a shaft mounted at a side of said member, work cutter carrying means mounted for reciprocatory movements on said shaft, and means connecting said cutter carrying means and said member operable to impart both forward and backward reciprocatory movements to said carrying means when said member is continuously moved in one 105 direction. 110
25. In a machine of the class described, means for successively acting on a forwardly feeding work piece to weaken the same at longitudinally spaced points, rotatable means disposed with its axis lengthwise of the feeding movement of the work and having radially disposed pockets into which the work successively enters as it feeds lengthwise of said means, said means 120
- 125
- 130

also having striker parts for coacting with and imparting a transverse strain on the work to break it in two at weakened points therein when said means is rotated, and 5 means for imparting intermittent rotary movements to said work receiving means.

26. In a machine of the class described, means through which a work piece is fed at a predetermined speed, a yielding pressure member over which the work feeds at a predetermined point in its movement, a guide disposed at one side of the path of feed of the work and paralleling the same, mechanism guided for reciprocatory movements 15 by said guide and having a part extending horizontally from said guide and carrying a cutter over the work, and means coöperating with said mechanism to cause the cutter part thereof to lower into contact with the work 20 at a point over said pressure member and to then raise out of contact therewith.

27. In a machine of the class described through which a work bar or tube continu-

ously feeds, a rotary member having successive pockets into which the work feeds and 25 operable to break off portions of the work, and means for intermittently rotating said member in predetermined timed relation to the movement of the work whereby the work is successively broken into predetermined 30 lengths by said member.

28. In a machine of the class described through which a work bar or tube continuously feeds, means operable to act on the work at longitudinally spaced points to 35 weaken the same, and rotary means operable to successively break sections from the work at the weakened points and to deliver the broken-off sections therefrom, the axis of 40 said rotary means being disposed longitudinally to the feed of the work and transversely to the delivery of the work sections from the rotary means.

In testimony whereof, I have hereunto signed my name to this specification.

EDWARD DANNER.
